ELECTRIC STOVE

Filed March 15, 1924

Patented Aug. 30, 1927.

1,640,371

UNITED STATES PATENT OFFICE.

CHARLES A. PIERSON, OF TOLEDO, OHIO, ASSIGNOR TO THE STANDARD ELECTRIC STOVE COMPANY, OF TOLEDO, OHIO, A CORPORATION OF OHIO.

ELECTRIC STOVE.

Application filed March 15, 1924. Serial No. 699,514.

This invention relates to electrical cooking apparatus of the type of stoves and ranges.

This invention has utility when incorporated in built-in electrical stoves for apartments, houses and general kitchen uses.

Referring to the drawings:

Fig. 1 is a front elevation with parts broken away of an embodiment of the invention as an electric range;

Fig. 2 is a side view of the range of Fig. 1, parts being broken away; and

Fig. 3 is a perspective view of the range housing.

15 The room is shown as having a floor 1. A side wall 2 upwardly extends therefrom to form a straight wall side region, which has continuous straight floor line 3. Above this floor line 3 is opening 4 in the side wall 2. This opening 4, in its lower portion, has electric current supply conduit 5. Over its upper portion this opening 4 has way or vent 6 as a flue section extending to riser flue 7.

25 This opening 4 is such that there may be freely inserted thereinto housing 8 having opening 9 in its bottom for registering with the conduit 5. There is also upwardly extending throat 10 from the housing 8 in communication with the flue section 6. This housing 8 has front opening 11 from which outwardly extend flanges 12, 13, to abut the wall 2 as surrounding opening 4. Should it be desired to further anchor the housing 8 against shifting as to the opening 4, such may be accomplished by bolts 14 through the flanges 12, 13, for engagement into the masonry, studding, or other framing for the opening 4.

40 This housing 8 is completed as a pocket for a cooking unit preferably by a surrounding trim or endless flange comprising side sections 15 and end sections 16 connected by corners 17, all anchored with the flanges 12, 13, of the housing 8.

The range proper is shown as comprising a cooking section 18 having switches 19 in front of heating elements 20. Over these heating elements 20 are seats 21 for cooking vessels. The lower front portion below the switches 19 has drop door 22 which permits opening into broiler section of this range. From the conduit 5 electrical connections 23 extend to distribution panel 24 back of plate 25 which may have automatic cut out

switch 26, light 27 and stop clock 28, having controller 29.

From this panel 24 the electrical connections extend to the series of switches 19 which series of switches 19, besides controlling the hot plate or cooking and broiling section, also control heating elements 30 in oven section 31. This oven section 31 is shown as provided with front door 32 having thermometer 33 therein. From the cooking section as well as from the broiling section there is vent back of the oven section 31. This vent 34 discharges through the throat 10. The hot plate section is herein shown as projecting slightly or partially 70 from the housing 8. There is also shown as projecting from the upper trim section 16 a hood 35 taking fumes from the opening of the oven door 32 as well as any fumes from the cooking which may not pass by the vent 34. Such fumes as come into this hood 35 also pass by way of the throat 10 into the flues 6, 7. The opening or ventilation action may be controlled by damper 36 in the throat 10 controlled by bar 37 disposed 80 in the hood 35.

The device disclosed herein is compact, provides a clear floor space and has full provision for the normal demands of household cooking.

What is claimed and it is desired to secure by Letters Patent is:

1. In combination, a casing having top, bottom, sides and back and open at its front, a range unit mounted in the lower portion 90 of the casing, an oven unit mounted in the upper portion of the casing in vertically spaced relation to the range unit and co-operating with the casing to form an exit flue leading upward from the space between 95 the two units.

2. A cooking apparatus having in combination, a casing having top, bottom, sides and back and open at its front, a range unit mounted in the lower portion of the casing, 100 and an oven mounted in the upper portion of the casing and co-operating therewith to form flues leading both from the upper front portion of the oven unit and from the space between the range and oven unit to an 105 exit point.

3. A cooking apparatus having in combination, a casing with top, bottom, sides and back and an open front, an electric range unit mounted in the lower portion of the 110

casing, an upper unit mounted in the upper portion of the casing in vertically spaced relation to the range units and co-operating with the casing to form an exit flue from the space between the two units, and means between the two units co-operating with the casing to form a chamber for receiving different control parts of the apparatus.

4. In a cooking apparatus, the combination of a casing adapted to be set into a wall opening and having top, bottom, sides and back and an open front, a range unit mounted in the lower portion of the casing and projecting forwardly from the same, an oven unit mounted in the upper portion of the casing in vertically spaced relation to the range unit, and co-operating with the casing to form flues leading over the oven unit in advance thereof and leading upwardly from the space between the two units to a point of exit from the casing, and means disposed within the space between the two units and co-operating with the casing to form a chamber for receiving different control parts for the apparatus.

5. In a cooking apparatus, the combination of a casing adapted to be set into a wall opening and having top, bottom, sides, back and an open front, a range unit detachably mounted in the lower portion of the casing, an oven unit detachably mounted in the upper portion of the casing in vertically spaced relation to the range unit and co-operating with the casing to form a flue leading from the space between the two units, and control means for the range and oven mounted in accessible position within the casing.

6. The combination with a room wall having an opening therein, of a casing set into the opening with its front side open to the room and having an outlet flue at its top portion leading to the outer side of the wall, a range top set into the lower portion of the casing, an oven set into the casing above the range top in spaced relation thereto and in spaced relation at its rear and top sides to the casing to provide flues therebetween in communication with the outlet flue, the space between the range top and oven being in communication with the rear flue, and a hood at the front end of the top flue overhanging the front side of the oven to direct fumes into the top flue from the oven when the oven door is open.

7. The combination with a room wall having an opening therein, of a casing set into the opening and open at its front side to the room and having an outlet flue at its top portion, a range top and an oven mounted in the casing in vertically spaced relation, the oven co-operating with the casing to form a flue which leads from the space between the range top and oven to the outlet flue, and a baffle plate removably mounted in the

rear portion of the casing in spaced relation to its rear wall and between the range top and oven to protect parts at the rear thereof and to assist in directing fumes into the lower end of the rear flue.

8. The combination with a room wall having an opening therein, of a casing mounted in the opening and having its front side open to the room and provided at its top with an outlet flue, an oven set into the upper portion of the casing in spaced relation to its rear and top sides to form respective rear and top flues therebetween in communication with the outlet flue, means forming a bottom oven and a range top plate in the lower portion of the casing in vertically spaced relation to the top oven, the lower oven and the space between the top plate and upper oven being in communication with the lower end of the rear flue, electrical heaters for the ovens and top plate, wiring parts for the heaters disposed within the casing at the rear of the space between the top plate and top oven, and a protecting plate for the wiring parts removably disposed in advance thereof between the top plate and top oven.

9. The combination with a room wall, having an opening therein, of a casing set into the opening and having its front side open to the room and provided with a top exit flue leading to a point exteriorly of the room, lower and upper sets of side flanges in the casing, a range top plate mounted on the lower set of flanges, an oven mounted on the upper set of flanges in spaced relation to the rear and top sides of the casing to form flues therebetween in communication with the outlet flue, the rear flue being in communication with the space between the top plate and oven, and the top flue communicating at its front with the interior of the oven when the oven door is open, and a baffle plate mounted on the lower set of flanges at the rear of the top plate and extending upward and rearward to near the bottom of the oven.

10. A structure providing a wall for a room, said wall having an opening, an open front housing in said opening, and a vent flue from said opening, an electric range section disposed in said housing to protrude through said open front, said housing having a flange for abutting the wall about said opening, and in addition to said housing and mountable independently thereof a trim between the opening and the range section including a hood in communication through said housing past said range section with said flue.

11. A structure providing a floor and a wall for a room, said wall having an opening spaced from the floor, an electrical supply conduit extending upwardly into the bottom side of the opening, a panel to which the conduit extends, a cut out switch in said

- panel, an electric cooking apparatus within said opening, to be partially housed in and fully supported by said opening surrounding wall, and cooking controlling electrical devices for said apparatus. 5
12. A structure providing a floor and wall for a room, said wall having an opening spaced from the floor, an electrical supply conduit extending upwardly into the bottom 10 side of the opening, an electric cooking apparatus within said opening to be partially housed in and fully supported by said opening surrounding wall, an electric current distribution section in the back of the apparatus, and connections from the conduit to said section. 15
13. A structure providing a floor and wall for a room, said wall having an opening spaced from the floor, an electric supply conduit extending upwardly into the bottom of 20 said opening, a flue from the upper portion of said opening, an electric stove within said opening and provided with vent connection with said flue, a cut out switch to which said conduit extends, and cooking controlling electrical devices for said stove. 25
14. A structure providing a floor and wall for a room, said wall having an opening spaced from the floor, an electric supply conduit extending upwardly into the bottom of 30 said opening, there being a flue from the upper portion of said opening, an electric stove within said opening and having vent connection with said flue, a cut out switch to
- which said conduit extends, cooking controlling electrical devices for said stove, and a trim between the opening and stove. 35
15. A structure providing a floor and wall for a room, said wall having an opening spaced from the floor, an electric supply conduit extending upwardly into the bottom of 40 said opening, there being a flue from the upper portion of said opening, an electric stove within said opening and having vent connection with said flue, a cut out switch to 45 which said conduit extends, cooking controlling electrical devices for said stove, and a trim between the opening and stove, said trim being endless and against the wall in the plane of said wall. 50
16. A structure providing a floor and wall for a room, said wall having an opening spaced from the floor, said opening having a vent flue from its upper portion, an electric stove within said opening, said stove comprising a cooking section, thereover an oven section, and an intermediate electrical distribution section, an electric supply conduit to the lower portion of said opening, electrical connection between said conduit and the distribution section, a cut out switch at 55 said distribution section, cooking controlling electrical devices for said stove, and a trim provided with a hood connected to the vent section. 60

In witness whereof I affix my signature.

CHARLES A. PIERSON.
